UNITED STATES PATENT OFFICE.

JOHN M. KRAMER, OF MARIA STEIN, OHIO.

LEVELING APPARATUS FOR STEAM-BOILERS.

SPECIFICATION forming part of Letters Patent No. 339,790, dated April 13, 1886.

Application filed October 2, 1885. Serial No. 178,805. (No model.)

To all whom it may concern:

Be it known that I, JOHN M. KRAMER, of Maria Stein, in the county of Mercer and State of Ohio, have invented a new and Improved 5 Leveling Apparatus for Locomotive Steam-Boilers, of which the following is a full, clear, and exact description.

The object of my invention is to provide a new and improved apparatus for leveling 10 steam-boilers automatically.

The invention consists of a pendulum provided with arms which operate valves, of a cylinder which is connected by a pipe with the water-compartment of the boiler, and of a 15 device for regulating the movement of the pendulum.

The invention also consists in various parts and details hereinafter more fully set forth and described.

20 Reference is to be had to the accompanying drawings, forming part of this specification, in which similar letters of reference indicate corresponding parts in all the figures.

Figure 1 is a side elevation, partly in section, of my improvement attached to a portable boiler standing on a level. Fig. 2 is a similar view of my improvement attached to a portable boiler passing down an incline. Fig. 3 is a like view of my improvement attached to a portable boiler going up an incline. Fig. 4 is a sectional elevation of a modification 30 of the pendulum-regulating device. Fig. 5 is a sectional side elevation showing the mounting of the pendulum; and Figs. 6 and 7 are detail sectional views showing the position of the valves in the pipes.

The boiler A, of usual construction, is provided on one end with one or two cylinders, B, having a piston, C, to which is attached a piston-rod, D. The lower end of the piston-rod D is provided with a roller, D', which rests on a guide, E', attached to the bolster E of the truck of the boiler. The front end of the boiler A is thereby supported on the fixed piston C. The upper end of the cylinder B, above the piston C, connects, by the pipe F, with the water-compartment of the boiler A, and another pipe, G, which leads from the upper end of the cylinder B to the open air, but may lead to a tank or other suitable receptacle or to a pump which connects with the boiler. The pipes F and G are each provided with a valve, F' or G', respectively.

The pendulum H is mounted on the top of the boiler A, preferably in the manner as 55 shown in Fig. 5. The pendulum hangs free on the side of the boiler A, and is provided with a slot, H'. To the pendulum H are pivotally attached and adjustable in the slot H' the arms I and I', which connect with the levers J and J', operating the valves F' and G', respectively. The upper end of the pendulum H is also provided with a rigid arm, K, to the outer end of which is pivotally attached the piston-rod L, provided with the piston M, 65 working in the small cylinder N, fastened in any suitable manner to the boiler A, and filled above and below the piston M with either oil, air, water, or other suitable substance. The upper and lower ends of the cylinder N are 70 connected with each other by the pipe O, provided with a valve or cock, P.

A communication between the upper and lower ends of the cylinder N can be established in the manner shown in Fig. 4, in which the piston-rod L' is hollow and provided with the transverse opening L' above the piston M', and an adjustable rod or plunger, Q, placed in the hollow piston-rod L', serves to close or open the transverse openings L', thereby connecting or disconnecting the upper and lower ends of the cylinder N, and also regulating the flow of the substance in the cylinder N from one end to the other when the piston M' is raised or depressed.

It will be understood that the apparatus above described is to be used with boilers of traction or road engines, railroad-locomotives, ships, and with all boilers that will from time to time change their position from 90 a horizontal plane. Its utility on road-engines is that it will keep the boiler in a horizontal position when the engine is going up and down hill, and the same action is produced in the case of locomotive-boilers, where 95 the engine has to travel over roads that cross mountains and hills, and on ships when rising and falling with the waves. By keeping the boiler level the flues and fire-box are prevented from burning.

100 It has been found in practice that the great drawback to the use of steam-engines on ordinary roads is that the boiler burns out so soon, as the water leaves one end or the other in passing over hilly ground, and the burning 105 of the boiler ensues.

The operation of my improved leveling apparatus is as follows: When the boiler A is in the normal horizontal position, as shown in Fig. 1, the valves F and G are both closed and the cylinders B are filled with water above the piston C, which is then in a midway position. When the truck passes down an incline, as shown in Fig. 2, the pendulum H assumes an inclined position to the center line of the boiler A and swings to the right, thereby opening the valve F' by means of the arm I and the lever J, so as to admit water under pressure in the boiler from the same into the cylinder B by means of the pipe F, and thereby forcing the cylinder B and the front end of the boiler E upward, (the boiler being adapted to move vertically on its rear axle as a pivot,) until the pendulum and the boiler are again in the normal position and the valve F is again closed. During the time that the valve F' is opened and closed again the valve G remains closed, although moving. As soon as the truck reaches a horizontal position again, the pendulum H swings to the left, whereby the valve G' is opened, and the water which had been admitted into the cylinder B is forced out of the same through the pipe G until the piston reaches its normal position (shown in Fig. 1) and the pendulum also has returned to its normal position and has closed both of the valves F' and G'. When the truck passes up an incline, as shown in Fig. 3, the pendulum swings to the left, thereby opening the valve G by means of the arm I' and the lever J'. The weight of the front end of the boiler causes the water above the piston C to flow out by means of the pipe G and the open valve G', so that the boiler with its front end swings downward until the pendulum and the boiler are again in the normal position and the valve closes, while the valve F' comes back to its normal position. When the truck reaches a horizontal position, the pendulum H is swung to the right so as to open the valve F', and thereby admit water under pressure from the boiler to force the piston C in the cylinder B downward until it reaches its normal position, (shown in Fig. 1,) and at the same time the pendulum will assume the normal position and close both valves F' and G'. It will be seen by reference to Figs. 6 and 7 that the valves F' and G' are so arranged that when the arms I and I' move in the direction of the arrow a' the valve F' is opened, while the valve G' remains closed, although moving, and when the arms I and I' move in the direction of the arrow b' the valve G' is opened and the valve F' remains closed, although moving. It will be seen that as the pendulum H assumes a vertical position while the boiler A is inclined the piston M changes its position in the cylinder N, which change is regulated by the speed with which the substance in the cylinder N flows from one end of the cylinder N to the other by means of the connecting-pipe O and the valve P. If the valve P is

closed entirely, so that there is no connection between the ends of the cylinder N, then the piston M and the pendulum H are prevented from moving.

I may use one cylinder B on each side of the boiler A, in which case the shaft on which the pendulum H is hung is extended to the other side of the boiler and provided with an arm, to which similar arms, as the arm I and I', are attached. The other arrangements, with the cylinder being the same as those shown in the drawings, an independent pendulum on each side with like arrangements on both sides may also be used.

Any suitable device for compensating for leakage in the cylinder N may be used.

The apparatus can be attached to stationary, marine, or any other boiler.

Having thus described my invention, what I claim as new, and desire to secure by Letters Patent, is—

1. In an apparatus for leveling boilers, the pendulum H, the arms I and I', the levers J and J', the pipes F and G, and the valves F' and G', in combination with the boiler A, the cylinder B, the piston C, and the piston-rod D, resting on the bolster E of the truck-frame, substantially as shown and described.

2. In an apparatus for leveling boilers, the boiler A, provided with a cylinder, B, the piston C, and the piston-rod D, resting on the bolster E of the truck-frame, in combination with the pendulum H, operating the valve F', attached to the pipe F, which connects the cylinder B with the water-compartment of the boiler A, substantially as shown and described.

3. In an apparatus for leveling boilers, the boiler A, provided with a cylinder, B, the piston C, and the piston-rod D, resting on the bolster E of the truck-frame, in combination with the pendulum H, operating the valve G', attached to the pipe G, which leads to the upper end of the cylinder B, substantially as shown and described.

4. In an apparatus for leveling boilers, the pendulum H, having the arm K, in combination with the cylinder N, the piston M, the piston-rod L, and a device for connecting the upper and lower ends of the said cylinder N, as described, substantially as specified.

5. In an apparatus for leveling boilers, the boiler A, the cylinder B, the piston C, the piston-rod D, resting on the bolster E of the truck-frame, the pipes F and G, the valves F' and G', the levers J and J', and the arms I and I', in combination with the pendulum H, having a slot, H', the arm K, the piston-rod L, the piston M, the cylinder N, and a device for connecting the ends of the cylinder N, as described, all arranged substantially as specified.

JOHN M. KRAMER.
